J. R. ST. JOHN
HAND LOGS.

No. 8,074.

Patented May 6, 1851

UNITED STATES PATENT OFFICE.

JOHN R. ST. JOHN, OF NEW YORK, N. Y., ASSIGNOR TO JAS. RENWICK, GEO. F. BARNARD,
AND E. B. ST. JOHN.

HAND-LOG.

Specification of Letters Patent No. 8,074, dated May 6, 1851.

To all whom it may concern:

Be it known that I, JOHN R. ST. JOHN, late of the city of Buffalo, in the State of New York, now of the city of New York, State of New York, engineer and printer, have invented, made, and applied to use certain new and useful improvements in the fitting and construction of what are nautically known as "hand" and "ship" logs and used for 10 denoting the rate in miles per hour at which a ship moves in the water, which improvements I term "St. John's geared hand-log;" that these improvements comprise the combination of mechanical movements with the 15 common log-keel and the attachment to the log-line of a mechanical substitute for the common "log-ship" or piece of wood at the end of the line.

These improvements, on the common log, 20 register the length of log line run out, in any given time, so as to ascertain the rate of speed, in a more certain manner, by the application, and combination, of mechanical means not before employed together, for 25 such purposes; and for which improvements I received Letters Patent of the United States, to be issued to James Renwick, L. L. D., George F. Barnard, and Edward B. St. John, all of the city of New York, as 30 the assignees of me, the said JOHN R. ST. JOHN, and as the trustees of the St. John's Compass and Log Manufacturing Company, of the city of New York, and agreeably to a deed of trust executed by me on 35 the twenty-sixth day of May, one thousand eight hundred and forty nine, and that the said improvements are fully and substantially set forth, and shown, in the following description, and in the drawing annexed to, 40 and making part of this specification, wherein in the Figure 1 is a plan, Fig. 2, an elevation partly open; Fig. 3, is a section through the line A, B, of Fig. 2. Fig. 4 is a plan of Fig. 3, with the dial plate and 45 glass removed, to show the internal positions of the operative parts, under the dial plate. These four figures are all drawn at about the half size of the instrument, with the parts employed, as in place for use. The Fig. 5, is a sectional elevation of the substitute, 50 adopted by me, for the piece of wood, usually known as the "log ship," and is similar, in form, to a small parachute, or strong parasol; but will be herein designated 55 by the nautical term of the "log ship," to identify it with the use to which it is ap-

plied by me, and is, in this Fig. 5 shown as if in operation. The Fig. 6, shows the same, as Fig. 5, but with the becket ferrule, on the log staff, detached, as described here-
after, and the ship folded, as when drawing
on board after use. In these two Figs. 5
and 6, the log ship is shown, as about one-
sixth of the proper size for use. The detached
figures are separately referred to, and the
same letters and numbers, as marks of refer-
ence, apply to the like parts in all the sev-
eral figures.

In these C, is the main frame of metal,
with one handle, D, and a second handle E.
These handles are shown as secured on the
frame, but may be cast or made solid, with
the frame. On the upper and outer corner
of the handle E, is a pivot 1, carrying a
"fourteen" second log glass, F, made in the
usual manner.

a, is a shaft, sustained by center screws
2, 2, going through the frame sides, and en-
tering sockets in the ends, so that any loose-
ness, or any unusual strain, shall not disen-
gage the shaft a, from its place. This mode
of mounting the roll shaft is shown sec-
tionally, in Fig. 9.

x, x, are two flanches cast solid with the
shaft a, and turned and fitted, to receive the
heads, b, b. These have between them,
trundle staves 3, 3, and collectively form the
reel G, for the log line.

At 6, 6, two pieces to form the top and
bottom of a box H, are cast or made with
one side of the frame C, between that and
the log reel, and inclosed with a strip of
metal, screwed at the ends, with an opening
to pass the shaft a. Within this box H,
the end of the shaft a, is formed as a worm
wheel c, which gears into a wheel d, having
fifty-five teeth, and set on an arbor 5, the
foot of which steps in a pivot. The upper
end is prolonged through the top 6, of the
box H, so as to terminate as a squared top,
inside the index or dial box I, which is se-
cured by screws on the top of the box H.
The squared top of the arbor 5, receives
the first pinion wheel e, having twelve teeth,
which are beveled outward and downward,
and within the teeth, the underside is
formed as a collar, that lies into a counter-
sink in the head of the governing lever g.
This has an eye, to lie around the arbor 5,
and a fulcrum at 11, in the side of the box 100
I. Between the arbor 5, and fulcrum 11,
a keeper spring n, overlies the lever g, and

keeps that down, and the pinion *e*, at the lowest point, on the arbor *5*, except when the outer scale formed end *12*, of the lever *g*, is depressed, as hereafter described.

- 5 Within the box *I*, a pivot step *8*, in the center, takes the lower end of the arbor *7*, that carries the counter wheel *f*. This is made with forty teeth, beveling outward and upward, to gear fair with the teeth in the pinion *e*, when that is raised on the arbor *5*, by depressing the outer end of the lever *g*. The top of the arbor *7*, is drilled into, to receive a button topped pin, coming down through the glass *13*. This carries the index pointer, or hand, *9*, which overlies the index card *10*, the divisions on which will be explained hereafter. On the top of the box *I*, is a cover or hood *i*, having a hinge on which it swings, to open or shut, and a common button latch spring *14*, to keep it shut, when not in use.

- In the figs. 5, to 8, representing the substitute logship *K*, *p*, is the top of a hollow tube or handle *k*, with a circular set of fixed joints *15*, taking the top ends of the stretcher pieces *l*, *l*. These are connected by stretcher braces *16*, to the joints *17*, of the sliding tube *n*, which slides loosely on the hollow tube *k*. The short staff or handle *h*, is formed with the lower end of the part *p*, and around it is a tube *m*, that slides on the staff *k*, and enters the lower end of the tube *n*, between that and the handle tube *k*, and is made slightly conical, to hold well 30 between the tubes *n*, and *k*, at the point *18*, like a circular wedge, yet to start easy by a jerk, and having two eyes *o*, *o*, to which the two ends of a piece of log line *19*, are attached and at the bight *20*, the outer end 35 of the log line *4*, is attached, as also the end of the stray and draw home line *21*. The other end of this is attached through an eye *22*, to a prolongation *p*, of the tube *k*, above the joints *15*, *15*.

- 45 *q*, *q*, are the external edges of the covering, on the stretchers *l*, *l*, which covering may be made of thick sheeting linen or light sail duck, or any fit material and varnished.

- At *r*, is a small portion of lead, sewed on 50 to the inside, near or on one end of one of the stretchers, and exactly opposite, at *s*, a portion of cork is attached.

- The parts acting with the log line are shown sectionally and separately, in larger 55 size, in the detached Figs. 7 and 8, and connected together, for use, in the collective sectional Fig. 5.

- All the metal parts, except the frames in the log reel and log ship, should be made of 60 brass, as this is the stiffest and strongest metal, in proportion to weight, that is not speedily corroded, and destroyed, by the action of salt water, excepting the spring and hand.

- 65 The proportions, that give the rate in

miles per hour, by the index pointer and card, are as follows: The log line, rolled in successive fakes on the reel, will average about twenty-seven inches, as the circumference of each fake, and fourteen seconds, in the log glass, bearing the same proportion to one hour of time, that four hundred and twelve feet of log line, run out in fourteen seconds, bears to seventeen nautical or geographical miles, in distance, omitting fractions) the train of gearing, between the log reel and counter wheel, will give one entire revolution of the index hand, during fourteen seconds, when the ship is going at a speed of seventeen miles an hour, and in like proportion, for any less rate of speed, as less line is run off the reel, in the same time by the log glass. Should a ship be moving at more than seventeen miles an hour, more than one entire revolution of the index hand will be made, and whatever is then surplus, is to be added to the index, which will give the rate of motion, per hour, during the time of fourteen seconds. When thus prepared, and adjusted, the instrument 75 is to be used in the following manner: It is intended, that one man shall hold the reel in both hands, so that his right thumb shall readily press the scale piece, on the end of the lever *g*, the log glass *F*, being in the 80 situation shown by dotted lines, on Fig. 2, the pivot *1*, sustaining it, outside the handle *E*, directly over the forefinger of the man, who sees that the index pointer *9*, is at *o*, and the sand all in the bottom of the glass. 85 A second man throws the "log ship" with a sufficiency of stray line to reach the water, and allow the motion of the vessel to draw the log line taut, the conical tube *m*, being pushed in between the tubes *n*, and *k*, so as 90 to hold all the parts expanded, as shown in Fig. 5, (when overboard) before throwing, when the log ship will take the proper position in the water. The man, holding the 95 reel, may now instantly turn the log glass over with his forefinger, so that it takes the position shown by the full lines in Fig. 2; and instantly presses on the top of the log glass which presses down the scale *12*, and outer end of the lever *g*, raising the inner 100 end, of the lever thereby putting the pinion *e*, into gear with the counter wheel *f*. The 105 log line *4*, running off the reel, puts all the parts in motion, and the log man, keeping all steady, watches the log glass, until the sand has run out, then instantly turns the 110 glass with his forefinger; the keeper spring *h*, instantly depresses the lever *g*, and takes the pinion *e*, down, and out of gear with the counter wheel *f*, which stops directly, leaving the index pointer *9*, at the point it had reached on the index card *10*, at the time 115 the sand in the log glass had run out, and denoting the rate, per hour, in miles and fractions, at which the ship or vessel has 120 125 130

moved through the waters, during the fourteen seconds occupied by the sand running in the log glass, the second man now " hauls home," on the log line, this jerks the tube *m*, 5 from between the tube *k* and *n*, and off the handle *k*, leaving the log ship *K*, at liberty to turn end for end, and fold together, as it is shown in Fig. 6, with the stray line 21, taking the connection to the log line, by 10 which it is drawn on board the vessel, as the line is wound on to the reel, as now usually practiced.

The common hand log, as heretofore used, consists only in the log reel and line in a 15 frame, the outer end of the line being attached to three short pieces, usually called the becket, or crowfoot of the line, two of these parts are permanently attached to a three cornered, or segmental formed piece of 20 thin wood, usually termed the "log ship," that has a small piece of lead attached to one edge, just enough to make the "log ship" float edgewise in the water, with one edge flush with the surface; the third part 25 of the becket, or crowfoot, is usually attached to a peg, stuck into the lower angle, or curve, of the log ship, so that when overboard, the log ship and line are at right angles to each other: This, when thrown 30 overboard, runs the log line off the reel, but admits of lateral escape of the water, partly by the flatness of the surface, and partly by the smallness of the size; so that the "log ship" is not so stationary in the water, but 35 that it follows the ship, in a more or less degree, until the line is pulled home; this disengages the peg, at the lower angle, and throws the log ship flat on the surface of the water, by the fixed parts of the becket, near 40 the upper edge, when it is easily hauled on board the vessel. The length of line run out, after the stray line is gone, in a given number of seconds, as marked by knots, on 45 the log line, and timed by a sand glass, is usually assumed as a data, to ascertain the rate of the vessel through the water; but these modes are liable to uncertainty and error, from miscounting the number of knots run out, and not accurately allowing for the 50 stray line, at the commencement, but most importantly, from not starting to count, or stopping the log line, and turning or noting the last sand of the log glass, at the same instant of time, when either beginning or ending, or both; so that the actual rate of the 55 vessel is very rarely even approximated to, by these means.

With the gearing, attached as herein shown and described, between the log reel 60 and the index and glass, the length of the stray line, at the commencement, or ending the operation, is of no consequence; as if the lever *g*, is depressed, at the same instant the glass *F*, is turned, the "log ship," having hold on the water, runs off a given

length of line, in the fourteen seconds, and the lever being set free by the log man, at the instant the same has run down, the length of log line, run off in the time, moving the gearing as it runs off, gives the 70 rate in miles per hour, independent of what line has run off, before the glass is turned, to commence running the sand, and equally independent of what log line may run out, after the sand has run down, provided the 75 log man lets go the lever *g*, as the last sand descends, as all the line that runs off the reel afterwards, has not any effect on the 80 gearing, and recording parts, of the machine; so that these beginning, and ending their work, with the run of the sand, in the log glass, denotes the rate of the ship by mechanical means, acting with mathematical accuracy; though I do not mean to confine or limit myself to the mode shown, of arranging the gearing to a fourteen second log glass, but to vary both the glass and the 85 gearing, the drum included, by calculating the gearing to fit the glass, whether running a more or less number of seconds, so as to 90 obtain the same result, namely a mathematical measure of a ship's speed through the water, by the application of similar mechanical means to the common log reel and line already in use, and employed with a more 95 mechanically effective log ship such as herein described, which has both a larger spread, and deeper hold in the water, with a concave face, acting against the water, by which any lateral escape of the water is very much 100 lessened, if not entirely prevented; and the "log ship" remains so nearly stationary, while in use, that the effect of the pull on the line, by the motion of the vessel, does not cause any material error, in counting 105 the rate of the vessel's speed. In case of accident to the mechanism, the log reel may still be used, with a line marked in knots, in the usual manner, either with the parachute, or the common log now in use. 110

All the parts, taken separately, and described herein, as used by me for this purpose, are well known, and have long been applied to other uses; but I do not know of any invention in which the application, arrangement, and combination of these parts has been used, to produce an instrument, that through mechanical means, denotes with nearly or quite mathematical certainty, the rate, in miles per hour, at which a ship 115 or vessel travels through the water, during a fixed, limited, and known time. I therefore claim as new, and of my own invention, and desire to secure by Letters Patent of the United States—

1. The arrangement of the log glass *E*, lever *g*, pinion *e*, and wheel *f*, whereby the motion given to the clock work by the reel *G*, is communicated to the index *g* during a definite period of time, determined by turn- 130

ing the log glass on or off the lever *g*, the parts being so proportioned and the dial so divided, that the index, moving while the sand is running in the log glass *F*, shows the 5 rate of speed at which the vessel is moving per hour of time, during fourteen seconds, or any other known space of time; the parts being arranged, and operating substantially as described, or in a manner equivalent to 10 produce the same results, by like means.

2. The application of a parachute *K*, to the purpose of a "log ship," and the combination therewith of the cylindrical wedge *m*, or its equivalent, to enter between the 15 tubes *k*, and *n*, to keep the "log ship" *K*, spread, when in the water, and disengage when hauled on to "fetch home" so that the

log ship closes, and turns end for end in the water, and is easily hauled on board, said log ship being used with the reel and registering parts herein described and shown, or with any other means of supplying and determining the amount of line run out, during a known period of time, substantially as described and shown. 20

In witness whereof, I have hereunto signed my name in the city of New York, this seventh day of December one thousand eight hundred and forty nine. 25

JOHN R. ST. JOHN.
